UNITED STATES PATENT OFFICE.

FRANKLIN A. REECE, OF BROOKLINE, MASSACHUSETTS, ASSIGNOR TO THE REECE
BUTTON HOLE MACHINE COMPANY, OF BOSTON, MASSACHUSETTS, A CORPORA-
TION OF MAINE.

BUTTONHOLE SEWING MACHINE.

Application filed June 3, 1924. Serial No. 717,643.

This invention relates to buttonhole sewing machines of the type illustrated in my Patent No. 1,343,278, dated June 15th, 1920 and in my co-pending application Serial No. 280,704, filed March 5th, 1919.

The sewing machine illustrated in said patent and application comprises a main cam which makes one complete rotation during the formation of each buttonhole, during part of which rotation it operates to give the work a feeding movement for forming the edge stitches along the side of the buttonhole and during the remainder of which rotation it operates or controls barring mechanism for forming the bar at the end of the buttonhole. The device illustrated in said patent and application also has two separate feed devices for actuating the cam, one of which feeds the cam with a relatively slow movement while the latter is feeding the work and the other of which feeds the cam forwardly with a more rapid movement during the formation of the barring stitches.

One feature of my present invention relates to an improved means for feeding the main cam during the formation of the barring stitches so that said cam is always under positive control and all its movements are synchronized with the movements of the stitch-forming mechanism.

Such cam-controlling means is also constructed so that although it moves the cam forward intermittently during the formation of the barring stitches yet it positively brings the cam to rest at the end of each forward movement and also positively ensures that the cam will always be at a predetermined point at the completion of the barring stitches and at the time when the stitch-forming mechanism changes from barring stitches to edge stitches.

Another feature of my present invention relates to an improved barring mechanism which is constructed so that bars of different types can be made merely by effecting different adjustments in the parts.

Still another feature of the invention relates to an improved construction by which the center of oscillation of the needle bar carrier always has a predetermined position relative to the stitches being formed, whether these stitches are edge stitches or barring stitches.

Other features of my invention relate to various improvements in buttonhole sewing machines of this type all as will be more fully hereinafter set forth.

In order to give an understanding of the invention I have illustrated in the drawings a selected embodiment thereof which will now be described after which the novel features will be pointed out in the appended claims.

Fig. 23 is a development of the main cam.

Fig. 24 is a diagrammatic view showing one type of barring stitch which may be formed with this machine.

Referring now to the drawings 1 indicates generally the frame of the machine on which the operative parts are supported. The work in which the buttonhole is to be sewed 5 is retained in work-holding means herein shown in the form of a clamp plate 2 and work clamps 3 by which the work is clamped against the plate. This work-holding means is slidably mounted in ways 4 10 formed in the bed plate portion of the frame and it is given a back and forth movement during the forming of the side stitches on the buttonhole.

The stitch-forming mechanism herein 15 shown is similar to that illustrated in my patent and application and comprises a needle 5 operating above the work and a rotary hook or shuttle 6 operating beneath the work. The needle is supported by a 20 needle bar 7 which reciprocates in a needle bar carrier 8 and which derives its vertical reciprocation from a crank 9^x on the end of a horizontal shaft 10 which is geared at 11 to a vertical shaft 12, the latter in turn being 25 geared at 13 to the main drive shaft 14. The rotary hook is operated from the vertical shaft 12 through a shaft 15 which is geared to said shaft 12 by gearing 16.

The needle has a jogging movement so 30 that alternate thrusts are at the slit of the buttonhole and the other thrusts at a distance back from the slit. For this purpose the needle carrier 8 is pivoted at 9 and is connected through suitable connections 35 which will be hereinafter described to a lever 18 pivoted to the frame at 19 and carrying a follower 20 that operates in the groove of a switch cam 21 that is fast on the shaft 10.

40 The feeding movement of the work and also the forming of the barring stitches at the end of the buttonhole are under the control of a main cam indicated generally at 22 and which is mounted to rotate about an axis parallel to the axis of the drive shaft 14. This cam is a cylindrical cam which has formed in it a plurality of cam grooves 23, 24, 25 and 26. The cam groove 23 is that which controls the feeding movement 45 of the work and the cam grooves 24, 25 are those which control the barring operation.

The means for feeding the work herein 55 shown is similar to that illustrated in my above-mentioned patent and application and comprises an elbow lever 26 pivoted at 27 to the bed plate and having an arm 28 provided with a roll 29 that operates in the feed cam groove 23, the other arm 30 of said lever being slotted and being adjustably 60 connected by a link 31 to the clamp plate 2. This cam groove 23 is provided with the incline portions 32 which cause a swinging movement of the lever 26 and thereby a feeding movement of the work during the 65 formation of the edge stitches 34 and with

a straight portion 33 which holds the work stationary during the formation of the barring stitches.

This machine is constructed to make bars of different types depending on the shape 70 and contour of the cam grooves and upon the mechanism connecting said cam grooves with the needle carrier. The construction herein shown is specially adapted to form a bar of the type shown in Fig. 24 and which 75 consists of one or more short stitches 36 of the same length as the edge stitches 34 but which are situated centrally of the buttonhole and one or more longer stitches 35 also situated centrally of the buttonhole but of a 80 length considerably longer than the short stitch 36.

The machine is also constructed so that at all times during the stitching on a buttonhole the center of oscillation of the needle 85 carrier 8 will have the same relation to the stitches being formed. In making the buttonhole shown in Fig. 24, for instance, the center of the barring stitches are in the center line of the buttonhole indicated by the line 39 and the center of the edge stitches on the sides of the buttonhole are in the lines indicated at 37 and 38. With the present machine the center of oscillation of the needle bar carrier has the same position relative to the center line 39 of the buttonhole 90 while the barring stitches are being formed as it has to the center line 37 while the edge stitches 34 at the right of the buttonhole are being formed and said center of oscillation 95 further has the same relative position to the line 38 while the stitches 34 on the left hand side of the buttonhole are being formed as it has to the line 37 when the stitches 34 on the right hand side of the buttonhole are 100 being formed.

While different desired constant relations may be established between the center of oscillation of the needle carrier and the center of the stitches being formed I have 110 herein shown a construction wherein this center of oscillation is at all times in the center line of the stitches so that when the side stitches 34 on the right hand side of the buttonhole are being formed the center of oscillation will be in the line 37 while when the barring stitches are being formed the center of oscillation will be in the line 39 and while the edge stitches 34 at the left hand side of the buttonhole are being 115 formed the center of oscillation will be shifted so that it will be in the line 38.

The cam groove 24 is the groove which controls the position of the center of oscillation of the needle carrier and this is constructed so that when the stitches 34 on the right hand side of the buttonhole have been formed this center of oscillation will be shifted to the center of the buttonhole for the formation of the barring stitches at one 125 130

end of the buttonhole and when the barring stitches are completed the center of oscillation will be again shifted into the center line of the stitches on the other side of the buttonhole.

The cam groove 25 in the main cam is that which controls the change from the short barring stitch to the long barring stitch.

The construction herein shown by which the center of oscillation of the needle carrier is shifted from the line 37 to the line 39 and from the line 39 to the line 38 is somewhat similar to the barring mechanism illustrated in my above-mentioned patent and application.

The needle carrier 8 is pivotally mounted in two blocks 40 that are slideable transversely in ways 41 formed in the frame. These blocks have connected thereto a toggle device in the form of two toggle links 42, 43, the link 42 being pivotally connected to the blocks and the link 43 being pivotally connected to the frame at 44. By straightening or breaking the toggle device 42, 43 the blocks 40 are shifted transversely in their ways and by this means the needle carrier is shifted bodily thereby shifting bodily the center about which said carrier oscillates. The toggle device 43, 44 is connected by a link 45 to a lever 46 secured to a vertical shaft 47, the latter having an arm 48 thereon rigid therewith which carries a roll 49 that operates in the cam groove 24.

The cam groove 24 is formed with four straight portions 50, 51, 52 and 53 which are connected by inclined portions 54, 55, 56 and 57 respectively. Two of these inclined portions are in one direction and two in the other.

The roll 49 is traveling in the straight portions 50, 51, 52, 53 while both the side stitches and the barring stitches are being formed and the inclined portions 54, 55, 56 and 57 operate to shift the center of oscillation of the needle carrier after the edge stitches on each side have been formed and after the barring stitches at each end have been formed. This is illustrated graphically in Figs. 19 to 22. Fig. 19 illustrates diagrammatically the position of the needle carrier, toggle device 42, 43 and lever 46 during the formation of the edge stitches 34 on the side of the buttonhole that is stitched first. At this time the roll 49 is traveling in the straight portion 50 of the cam, which, it will be noted, is of the same length as the inclined feeding portion 32 of the feeding cam groove 23. At this time the center 9 of oscillation of the needle carrier is in the center line of the row of stitches being formed or in the line 37, Fig. 24.

During the time that the stitches 34 on the side of the buttonhole are being formed the roll 29 of the feeding lever 26 is operating in the inclined portion 32 of the cam groove 23

thus gradually feeding the work, and the main cam 22 is being fed forwardly by the slow speed driving mechanism. After the edge stitches 34 are completed then the roll 29 passes from the inclined portion 32 into the straight portion 33 thus maintaining the work-holding means stationary while the barring stitches 35, 36 are being formed. During the formation of the barring stitches 35, 36 the main cam 22 is actuated by another driving mechanism which feeds the cam forward at a faster rate and during the time that it is moving forward at the higher speed it is positively fed in timed relation with the reciprocation of the needle bar. During this positive feeding of the cam in timed relation with the reciprocation of the needle bar the center of oscillation of the needle carrier is shifted from the line 37 to the line 39 and the barring stitches are formed and then the center of oscillation is shifted to the line 38 at the other side of the buttonhole at which time the cam is again actuated by the slow speed driving mechanism for forming the stitches 34 at the other side of the buttonhole.

When the edge stitches on one side of the buttonhole are completed the roll 49 passes through the short inclined portion 56 of the cam groove 24 thus shifting the lever 46 slightly into the position shown in Fig. 20. This will break the toggle lever 43, 44 to a greater extent and thus move the blocks 40 laterally in Fig. 3 which will result in shifting the center 9 of oscillation of the needle carrier into the center line 39 of the buttonhole. The roll 49 then passes into the straight portion 53 of the cam groove 24 thus holding the parts in this position and while the portion 53 of the cam groove is operating both the short barring stitches 36 and the long barring stitches 35 are formed. When these stitches have been completed the roll 49 passes into the short inclined portion 57 of the cam groove which again shifts the lever 46 and brings it into the position shown in Fig. 21. This breaks the toggle lever 43, 44 still more and shifts the blocks 40 still further laterally in Fig. 3 thus carrying the center 9 of oscillation of the needle carrier into the center line of the stitches 34 on the opposite side of the buttonhole, which is the center line 38 in Fig. 24. At this time the roll 29 of the feeding cam enters the inclined feeding portion 32 thereby feeding the work while the edge stitches are formed on the other side of the buttonhole.

During this time the roll 49 operates in the straight portion 50 of the cam groove and when the stitches on both sides of the buttonhole have been completed the roll 49 passes into the short inclined portion 54 of the groove 24 thus shifting the lever 46 into the position shown in Figs. 20 and 22 and bringing the center of oscillation into the center

line 39 of the buttonhole. The barring stitches 35 and 36 on the last end of the buttonhole are then formed, this being done while the roll 49 is travelling in the straight portion 51 of the cam groove. When these stitches are formed the roll 49 passes into the short inclined portion 55 thus again shifting the lever 46 into the position shown in Fig. 19 and bringing the center of oscillation into the center line 37.

Where the long and short barring stitches 35 and 36 are desired I propose to use the connection between the switch cam and the needle carrier which is illustrated best in Fig. 3.

The arm 18 which carries the follower 20 that is actuated by the switch cam, is connected by a link 58 to a rocking member 59 that is pivoted at 60 to the frame 1. This 20 rocking member 59 is in turn connected to the needle carrier by a link 61. The pivotal connection between the link 61 and the rocking member 59 is adjustable so that said connection may be moved further from or nearer 25 to the center 60 of oscillation, thereby to vary the amplitude of movement given the needle carrier by the oscillatory movement of the lever 18 which, it will be remembered, has a fixed amplitude of movement.

30 For this purpose the member 59 is shown as having a slotted arm or extension 62 in the slot 63 of which the pivotal connection 64 between the link and the member 59 is received. When the link 61 is in the position 35 shown in full lines Fig. 3 at the lower end of the slot the needle carrier will have a minimum amplitude of oscillation but if the arm 62 is swung into the dotted line position Fig. 3 then the needle carrier will have 40 an increased amplitude of movement.

During the formation of the edge stitches 34 on the buttonhole and the formation of the short barring stitches 36 the link 61 is in the position shown in full lines Fig. 3.

45 When the long barring stitches 35 are to be formed the link 61 is swung into its dotted line position Fig. 3 thus giving the needle carrier the long amplitude of movement sufficient to form these long stitches 35. This 50 is accomplished by the cam groove 25. Operating in this groove 25 is a roll 65 carried by a lever or arm 66 rigid with a rock shaft 67, the latter having fast thereon an arm or lever 68, the end of which is adapted to 55 engage the end of the link 61. This arm 68 is formed with a curved surface 181 which engages a roll 182 carried by the link 61 so that when the lever 68 is swung into the dotted line position Fig. 3 the link 61 will 60 be moved to the end of the slot 63 as shown in dotted lines. The curved surface 181 is formed on a radius struck from the center 60 when the member 68 is in the dotted line position Fig. 3, and the reason for this is so 65 that when the parts are in said dotted line

position Fig. 3 the back and forth movement which the roll 182 has due to the operation of the switch cam 21, will be in an arc struck from the center of oscillation of the member 62 and thus the position of the 70 link relative to the arm 62 will remain unchanged.

The link 61 has connected thereto a return spring 70 which returns it to the full line position when the lever 68 is returned 75 to full line position and in the present construction this return spring is connected to the curved end 69 of the arm 68. The movement of the arm or lever 68 from the full to the dotted line position and vice versa is 80 secured by the cam groove 25.

It will be noted that this cam groove is straight throughout the greater portion of its length but it has the two curved portions 71. When the roll 65 enters either of the 85 portions 71 the lever 68 is swung into the dotted line position Fig. 3 thereby shifting the link 61 from its full to the dotted line position and holding it there until the long barring stitches 35 have been formed, after 90 which the lever 68 is returned to its normal position, the spring 70 acting at the same time to return the link 61 to the full line position Fig. 3.

The mechanism shown in Fig. 3 operates 95 to maintain the center of oscillation of the needle carrier in the center line of the edge stitches while the latter are being formed and shifts its center of oscillation to the center line of the buttonhole while the barring stitches are being formed. It also operates to produce one or more short barring stitches 36 and then one or more longer barring stitches 35. This form of bar is 100 advantageous because the short barring stitches 105 act to tie the sides of the buttonhole together at the end of the slit and the long barring stitches reinforce this and also form a proper finish to the buttonhole.

The construction herein shown provides 110 for making a buttonhole with the side stitches 34 of greater or less length. This is accomplished by providing an adjustable connection between the link 58 and the lever 18 whereby the amplitude of movement of 115 the needle carrier may be varied. The lever 18 is slotted as shown at 72 and the pivotal connection 73 between the link and lever is adjustable in the slot. An adjustment away 120 from the center 19 of oscillation will lengthen the stitches 34 while an adjustment in the opposite direction will shorten the 125 stitches.

It is obvious that when the stitches 34 are increased in length the two center lines 37, 38 will be more widely separated from each other while if these stitches are decreased in length the center lines 37, 38 will be brought nearer each other. It will also be 130 obvious that when long stitches 34 are being

formed the distance which it is necessary to shift the center 9 of oscillation to carry it from either line of stitches 34 to the center line of the buttonhole is greater than required when the stitches 34 are short stitches and the center lines 37, 38 are relatively near together.

To provide for this the connection between the link 45 and the lever 46 is an adjustable one, said lever having a slot 74 in which the pivotal connection 75 is adjustably received. By adjusting this connection 75 away from the center of oscillation 47 the movement of the lever 46 will produce a greater movement in the toggle device 42, 43 and thus a greater movement of the center 9 of oscillation of the needle carrier, while adjusting the pivotal connection 75 toward the center of oscillation 47 will produce shorter shifting movement of the needle carrier. The connection 75 will, therefore, be adjusted in the slot 74 to correspond to the length of the stitches 34.

Whenever the adjustment of the parts is changed in making the change from a buttonhole having short edge stitches 34 to one having long edge stitches by shifting the pivotal connections 73 and 75 it is necessary that during such shifting the center of oscillation should be moved out slightly so that it will be automatically brought into the center line of the longer stitches 34. To accomplish this I have herein shown the following construction.

The slot 74 is formed on the arc of a circle struck from the center midway between the center 9 of oscillation of the needle carrier and the axis 44 of the arm 43 so that if the links 42 and 43 are of equal length the pivotal connection 75 may be moved in the slot 74 without changing the position of the toggle lever. The link 42 is longer than the link 43 so that the pivotal point at which said links are connected is offset slightly from the center of the curve 74, or in other words the curve 74 will then be slightly eccentric to the pivotal connection between the links 42, 43. Where this construction is employed a shifting movement of the pivotal connection 75 toward the outer end of the slot 74 will result in straightening the toggle device 42, 43 slightly thus moving the center of oscillation of the needle carrier outwardly. This eccentric relation is so designed that when the connection 75 is properly positioned in the slot 74 for a buttonhole having edge stitches 34 of any predetermined length the center of oscillation of the needle will always be located in the center line of said edge stitches.

I have stated above that the main cam 22 is driven from the shaft 14 by two separate driving mechanisms, one of which operates while the edge stitches 34 are being formed and the other of which operates while the

barring stitches are being formed, all as shown in my above-mentioned patent and application. The feed device which actuates the main cam during the formation of the edge stitches 34 is illustrated in Figs. 6 and 7. The shaft 14 has mounted thereon an eccentric 76, the eccentric strap 77 of which has an arm 78 rigid therewith which is pivotally connected at 79 to a ball clutch device. This comprises a clutch member 80 loosely mounted on the shaft 81 on which the cam 22 is mounted and having a plurality of pockets 82 with inclined faces 83, which pockets receive clutch balls 84 that are acted on by suitable springs 85. These balls engage the interior of the cam 22.

When the clutch member 80 moves clockwise in Fig. 6 the balls will be ineffective but when it is moved anti-clockwise the balls serve in a well known way to clutch the member 80 to the cam drum and thus move it forward. This makes an intermittently-acting clutch by which the drum 22 is stepped forward intermittently.

The eccentricity of the eccentric 76 may be adjusted in the manner illustrated in my patent and application by means of an adjusting member 86 slidably mounted on the shaft 14 and having an inclined portion 87 extending axially through the eccentric. This member 86 is controlled by a lever 88 pivoted at 89 to the frame, one end of the lever being forked and engaging in the groove 90 formed in the member 86. This feed device is constructed to give the cam 22 a relatively slow feeding movement necessary for the formation of the edge stitches 34. The other feed motion by which the cam is fed forward during the formation of the barring stitches is arranged to feed the cam faster and it also has the characteristic that it not only positively feeds the cam forward at each step but also positively maintains the cam at all times in timed relation with the reciprocations of the needle and further positively brings the cam to rest at the end of each step. As a result the cam 22 will invariably have a predetermined position at the time that the barring stitches are completed and the change is made from barring to edge stitches. This feed mechanism is best shown in Figs. 4 and 5.

The shaft 14 has fast on it an eccentric 91, the eccentric strap 92 of which has an arm 93 rigid therewith which is pivotally connected at 94 to a rocking member 95 that is loosely mounted on the shaft 81 of the cam drum 22. This rocking member 95 has pivoted thereto a feed pawl 96 which is adapted to engage ratchet teeth 97 formed on the interior of the cam drum 22. This rocking member has also pivotally mounted thereon at 98 a stop pawl 99 adapted to engage ratchet teeth 100 formed on the interior of the cam. The ratchet teeth 100 are disposed oppositely to 130

the ratchet teeth 97, and, therefore, when both pawls 96 and 99 engage their ratchet teeth as shown in Fig. 4 the cam drum is positively locked to the oscillating member 95. This is the position of the parts when the cam 22 is being moved forwardly by the pawl 96.

When the rocking member 95 comes to rest at the end of its forward movement and the eccentric has passed its dead center the pawl 99 is lifted out of engagement with its teeth 100 so that when the member 95 starts its backward movement said pawl 99 is released. This is accomplished by the following means.

Pivottally mounted on the shaft 81 is a sleeve 101 having a lug 102 adapted to engage a projection 103 extending from the locking pawl 99. This sleeve 101 has also an arm 104 extending therefrom, the end of which enters into a recess 105 formed in the member 93 and is acted on by a thrust pin 106 which carries at its inner end a roll 107 that engages a cam face 108 formed on the eccentric 91. This cam face is so disposed that when the eccentric has moved the rocking member 95 forwardly to the limit of its movement the high portion of the cam 108 will engage the roll 107 and move the thrust pin 106 to the right Fig. 4 thus turning the sleeve 101 against the action of the spring 109 and acting through the lug 102 and projection 103 to rock the locking pawl 99 into the dotted line position. This disengages it from the ratchet teeth 100 so that the rocking member 95 will be free to move backwardly without giving any backward movement to the cam 22. When the eccentric 91 is moving to the left Fig. 4 and the parts are ready for another forward movement, then the roll 107 passes onto the low portion of the cam 108 and the spring 109 returns the sleeve 101 to the position shown in Fig. 4 while the spring 110 will throw the pawls 96 and 99 into engagement with their respective ratchet teeth thus locking the cam drum 22 positively to the rocking member 95, and placing the parts in position for the next forward movement.

The ratchet teeth 97 and 100 extend only partially around the interior of the cam drum 22, the latter having smooth faces 111 and 112 with which the pawls engage while the edge stitches on the buttonhole are being formed. So long as the pawls 96 and 99 are operating on the smooth surfaces 111 and 112 the oscillating movement of the carrier 95 will have no effect in feeding the cam drum, this being the time during which the cam is fed by the slow feed device shown in Fig. 6. When the edge stitches have been completed, however, the cam has been brought into position so that it is fed forward by the pawl 96 and during each forward movement the cam is locked positively to the member 95 by

the dog 99 so that the cam will be positively moved forward a predetermined amount at each forward movement of the member 95 and will be brought to rest when said member 95 reaches the limit of its movement and just before it starts its return movement. The cam 22, therefore, is not only positively fed forward but is absolutely prevented from overrunning any at any forward step. It will be noted that at each forward step 75 the cam is stepped forward a distance equal to the space between two ratchet teeth 97 and that the amplitude of movement of the pawl 96 is equal to the distance between the ratchet teeth. The pawl 96 steps the cam 80 forward one step for each barring stitch and, therefore, the number of barring stitches which is formed is determined by the number of the ratchet teeth 97, there being the same number of barring stitches on the 85 buttonhole as there are ratchet teeth 97 on the cam.

It will, therefore, always be invariably positioned at a predetermined point at the end of the barring operation, which is an 90 important feature because each forward movement of the cam during the barring operation is much greater than it is during the formation of the edge stitches and if the cam were not always accurately positioned at the end of the barring operation or if there was any tendency for the cam to overrun said cam might be improperly positioned for forming the first of the edge 95 stitches on the buttonhole.

Another advantage which is gained by the use of the pawls 96, 99 and their ratchet teeth is that during the entire time between the formation of the edge stitches on one side of the buttonhole and the edge stitches on the other side of the buttonhole the cam 22 is being positively fed in absolute timed relation with the reciprocations of the needle with no possibility of any slippage occurring which will in any way disarrange such timed 105 relation. It will be noted that all of the relative positions of the work and the needle between the time that the edge stitches on opposite sides of the buttonhole are being formed are under the control of the main 110 cam and by having the main cam thus positively driven in absolute timed relation with the needle it is possible to use the same cam for forming the edge stitches and the barring stitches and with the absolute certainty 115 that the barring stitches will be always properly formed and the shifting of the work will occur always at the time that the needle is withdrawn therefrom.

This machine is intended for high speed 125 operation and in order to bring the machine to rest at the end of each cycle of operations with an easy movement and without undue shock or jar I have provided a novel driving and stopping mechanism which comprises 130

one driving member for operating the machine at a high rate of speed and until all but the last few stitches of the buttonhole are completed and have also provided a slow speed driving member and means for disconnecting the drive shaft from the high speed driving member just before the stitching operation is completed and for connecting it to the low speed driving member, which latter positively drives the shaft during the formation of the last stitches and until it is stopped by the stopping mechanism.

Each of the drive mechanisms comprises a belt driven pulley, the high speed drive mechanism including the pulley 113 and the low speed drive mechanism the pulley 114, the latter being driven at a slower speed than the former. The clutch for clutching the high speed belt pulley 113 to the shaft is shown in Figs. 8, 9 and 10. This comprises an internal expanding clutch ring 115 which is mounted on a stud 116 carried by the pulley 113 and which is adapted to frictionally engage an interior friction surface 117 formed on a member 118 that is fast to the shaft 14. The clutch member 115 is normally held in its contracted position by a spring 119 and it is expanded into clutching engagement with the clutch surface 117 by a cam member 120 mounted on a stud 121 that is carried by the pulley. This stud has a lever 122 rigid therewith carrying an adjustable projection 123 that is adapted to engage a cone surface 124 on a clutch-actuating sleeve 125 that is slidably mounted on the hub of the pulley 113. This sleeve 125 is provided with a groove which receives a yoke 126 connected to a lever 127, the latter being pivoted to the frame at 128.

When the lower end of the lever is moved to the right Fig. 2 the clutch-actuating sleeve 125 will be moved to the right Fig. 10 and the engagement of the cone portion 124 with the projection 123 will turn the arm 122 and thus turning the cam 120 and expanding the clutch ring 115 into clutching engagement with the clutch 118.

The controlling lever 127 is held in its inoperative position normally by a stop 129 which has connected thereto a finger piece projecting above the bed plate and by which the operator may disconnect the stop 129 from the end of the lever 127. The lever is shifted and the clutch is thrown by springs 130 which are shown as acting against a slide 131 mounted in ways 132 on the frame and connected to the end of the lever 127 by means of a link 133. The machine, therefore, is started in operation by the operator depressing the finger piece which releases the stop 129 from the lever 127 thus allowing the springs 130 to clutch the high speed pulley 113 to the shaft.

The low speed pulley 114 is clutched to the shaft by means of a device shown in Figs. 11

and 12. The member 118, which, it will be remembered is keyed to the drive shaft 14, has a clutch dog 134 pivoted thereto at 135. This dog is provided with a lateral clutch projection 136 which is adapted to engage a shoulder 137 formed on a member 138 that is associated with the slow speed driving pulley 114. The clutch dog 134 is acted on by a spring 139 which normally holds the clutch projection 136 in position to engage the shoulder 137 and when said projection is in engagement with the shoulder as shown in Fig. 11 the rotation of the member 138 is communicated through the clutch dog 134, and member 118 and therethrough to the shaft 14. The member 138 is yieldingly connected to the pulley 114. This member has a lateral extension 140 extending into a recess 141 formed in said face of the pulley and this projection is situated between two springs 142 that are located in spring-receiving recesses 143 formed in the side face of the pulley. The ends of the springs rest against a partition wall 144. The rotation of the pulley 114 is, therefore, communicated to the member 138 through one of the springs 142 thus making a yielding drive.

When the machine has come to rest at the end of a cycle of movements the clutch dog 134 is held in its inoperative position by means of a stop member 145 which is in the form of a pin carried by a housing 146 secured to the slide 131, said pin being backed by a spring 147. When the machine is started in operation by the shifting of the slide 131 to the right Fig. 2 the stop pin 145 is withdrawn from engagement with the tail 148 of the clutch dog 134 and the spring 139 then throws the latter into operative position. It will be remembered that this movement of the slide 131 serves to actuate the high speed clutch thereby connecting the high speed pulley 113 to the shaft 14 so that the latter is operated at a high speed. It will also be remembered that the pulley 114 is rotating at a slower rate of speed than the pulley 113.

The clutch dog 134 is pivotally carried by the member 118 which is fast on the shaft and, therefore, so long as the high speed clutch is in operation the clutch dog 134 will be rotating at the same speed as the pulley 113. Since the pulley 114 is rotating at a slower rate of speed the clutch dog 134 will travel faster than the clutch shoulder 137 which rotates with the slow speed pulley 114 and thus the clutch dog will overrun the clutch projection. Under these conditions the slow speed clutch is ineffective.

In order to prevent any clicking noise which may result from the clutch projection 136 riding over the shoulder 137 during this overrunning movement the clutch dog is so designed that at the high speed at which the pulley 113 is operating the centrifugal force

on the end of the dog carrying the projection 136 is sufficient to overcome the tension of the spring 139 and thus the clutch dog will be thrown by centrifugal force outwardly into an inoperative position in which the projection 136 travels in a path outside of the clutch shoulder 137.

The stopping of the machine is controlled by a stop cam 149 formed on the cam member 22, said stop cam operating on a projection 150 on the controlling lever 127. This stop cam is formed with the two rises 186 and 187 separated by a straight portion 188. As the cycle of operation is approaching its end the rise 186 engages the projection 150 on the lever 127 and gives said lever a slight movement which is sufficient to carry the slide 131 from the extreme right position Fig. 2 into the dotted line position. When 20 in this position the clutch actuator 125 has been moved into a position to allow the clutch 115 to be released by its spring 119 so that the high speed driving pulley 113 is freed from the shaft 14 and the machine 25 will continue to rotate by its own momentum. As soon as the high speed clutch pulley 113 has been thus disengaged from the driving shaft the machine will immediately begin 30 to slow down and thus the centrifugal force acting on the clutch dog 134 will be correspondingly lessened. When the machine has slowed down to a predetermined point 35 this centrifugal force will be insufficient to overcome the tension of the spring 139 and the latter will automatically swing the clutch dog 134 into its operative position with the clutch projection 136 in engagement with the shoulder 137. The slow speed driving pulley 114 is thus automatically coupled 40 to the shaft 14 and said shaft will be driven positively by the pulley 114. This takes place during the formation of the last few 45 stitches and while the roll 150 is operating on the straight portion 188 of the stop cam. 50 When the cam has turned sufficiently so that the roll 150 engages the second inclined portion 187 of the stop cam then the slide 131 is moved into this full line position Fig. 2 thus bringing the stop pin 145 into 55 the path of movement of the tail 148 of the clutch dog 134 and when this position is reached then on the next rotation of the pulley 114 said tail of the clutch dog will engage the cushioned stop member 145 thus 60 swinging the projection 136 out of engagement with the shoulder 137, which operation disengages the slow speed driving pulley 114 from the shaft 14. Since the clutch dog 134 is rotating with the shaft 14 the engagement of the tail 148 of the clutch dog with 65 the stop pin 145 will not only disengage the clutch but will also bring the shaft 14 to rest with a cushioning movement due to the cushioning effect of the spring 147.

65 With this construction, therefore, the ma-

chine will be driven at the high speed during the greater part of the sewing cycle of operations and when the cycle is about completed the high speed driving pulley is automatically disconnected from the driving shaft and the low speed pulley is automatically connected thereto so that during the remainder of the cycle the machine will be driven at a slow speed and will be positively driven up to the point at which it is stopped. 70 By this arrangement the speed of the machine can be slowed down to a predetermined point at the time the stop motion operates regardless of the speed at which the machine is normally running and, therefore, the stopping of the machine may be accurately effected with a minimum shock or jar. 75

There is another advantage resulting from this construction. It will be noted that the machine is brought to rest just after the barring stitches have been formed at the last end of the buttonhole and, therefore, while the cam 22 is being positively fed forward in timed relation with the reciprocations of the needle. Because of this positive connection 85 between the cam 22 and the reciprocations of the needle the slide 131 will always be moved from the dotted to the full line position Fig. 2 at a predetermined point in the rotation of the main shaft and, therefore, the 90 stopping of the machine will always be accomplished in the uniform manner. 95

Another feature involved in this construction is that the spring 130 which is used for throwing into operation the clutch which connects the driving pulley 113 to the shaft 14 is compressed and thus has energy stored up therein by the movement of the main cam. This operation is permissible because of the fact that the main cam is positively driven during the time that the slide 131 is 100 moved toward the left Fig. 2. 105

The machine herein shown also includes a buttonhole cutter for cutting the buttonhole, this being accomplished after the buttonhole is stitched. The buttonhole cutter is indicated at 151 and is actuated by means similar to that shown in my patent No. 1,343,387, June 15th, 1920. This cutter is connected to an oscillating member 152 pivoted at 153 110 and receiving its actuation from an eccentric 154 carried by a sleeve 162 which is loosely mounted on the shaft 14 and is driven from a driving pulley 155. The eccentric strap 156 of this eccentric is connected to a toggle 115 lever device comprising two connected links 157, 158, the latter being connected to the oscillating member 152 so that when the eccentric 154 is given a rotation the buttonhole cutter 151 will be given its cutting movement. 120

The driving pulley 155 is continuously operating but the eccentric 154 is normally disconnected therefrom. It is connected thereto by means of a clutch device shown in 125 130

Fig. 13 which is similar to that shown in Figs. 11 and 12 and by which the low speed clutch 114 is connected to the driving shaft 14.

5 The driving pulley 155 has associated therewith a member 184 which is yieldingly connected thereto by the springs 182 which lie in a recess formed in the pulley 155 and engage a projection 183 extending from the 10 member 184 and into the recess, this connection being similar to the connection between the pulley 114 and the member 138. The member 184 is provided with a clutch shoulder 159 which co-operates with a clutch dog 151 that is pivoted at 163 to a member 185 that is fast on the sleeve 162, which it will be remembered is loosely mounted on the shaft 14. The clutch dog has a projection 160 which co-operates with the clutch shoulder 159, this dog being in all particulars like the clutch dog 134 shown in Fig. 17 and being acted on by a spring 186 which normally tends to hold the projection 160 in engagement with the shoulder 159.

25 During the operation of sewing the buttonhole the clutch dog 161 is held out of engagement by the fact that the tail 164 thereof engages a stop pin 165 similar to the stop pin 145 as illustrated in Fig. 13. This 30 stop pin 165 is carried by a slide 166 which is slidable in ways 167 in the frame and which is acted on by suitable springs 168. This slide is connected to one end of a lever 169 pivoted to the frame at 170. The lever 35 is normally held in its inoperative position shown in Fig. 2 by means of a locking lever 171 which is pivoted at 172 and which is acted on by a spring 173. When the locking lever 171 is released from locking engagement with the lever 169 then the springs 168 will move the slide 166 toward the left, thus withdrawing the stop pin 165 from engagement with the tail 164 of the clutch dog and the latter will automatically come into action to clutch the pulley 155 to the member 185 thereby rotating the eccentric 154.

The locking member 171 is actuated to release the lever 169 by a cam projection 174 carried by the main cam 22, this being so disposed that just as the cam 22 completes its return at the end of the sewing cycle the member 171 will be released thus automatically coupling the pulley 155 to the mechanism for operating the buttonhole cutter.

55 The clutch by which the pulley 155 is connected to its buttonhole cutting mechanism is a one-revolution clutch so that it will be disengaged after the cutter has made one stroke. For this purpose the sleeve 162 is 60 provided with a cam surface 175 which is adapted to engage a pin 176 carried by the lever 169 thereby to return said lever to the full line position shown in Fig. 2 and to bring the stop pin 165 into the path of movement of the tail 164 of the clutch dog. As

the clutch dog completes its first rotation, therefore, its tail will engage the stop pin 165 and said dog will be thrown into its inoperative position thus unclutching the sleeve 162 from the pulley 155.

177 represents a stop dog pivoted at 178 to a bracket 201 secured to the frame 1 and acted on by a spring 179 which co-operates with a shoulder 190 formed on the sleeve 162 to prevent any rebound or recoil movement in said sleeve after it has been brought to rest. By thus holding the sleeve rigidly from backward movement the clutch dog will be held in its inoperative position out of the path of travel of the clutch shoulder. A similar device in the form of a stop dog 180 is employed to prevent recoil movement of the member 118 after the shaft 14 has been brought to rest. This stop dog 180 is pivoted at 285 and is adapted to engage a shoulder 181 formed on the member 118. It is acted on by a spring 284 and is provided with a tail 283 which is situated to be engaged by an arm 282 extending laterally from the control lever 127. This arm 282 70 serves to release the dog 180 when the lever 127 is shifted to clutch the driving pulley 113 to the shaft 14.

75 It sometimes happens that the thread breaks during the stitching on a buttonhole. In order to prevent the buttonhole cutter from operating under these conditions I have provided means whereby the operator may hold the lever 169 in the position shown in Fig. 2 even after the lever 171 has 80 been tripped. Such means is in the form of a spring-pressed plunger 196, the inner end 195 of which operates in a bearing 194 and when the plunger is pushed inwardly by the operator said end will engage the projection 193 on the end of the lever 169 and thus prevent the latter from operating when the lever 171 trips. With this attachment, therefore, the operator can complete the cycle of operations after the thread breaks 85 except for cutting the buttonhole.

90 While I have herein illustrated a selected embodiment of my invention I do not wish to be limited to the constructional features shown.

95 I claim:

1. In a buttonhole sewing machine, the combination with work-holding means movable only in a direction longitudinally of the buttonhole, of stitch-forming mechanism operating to form edge stitches along the two edges of the buttonhole in succession, said stitch-forming mechanism including an oscillating needle carrier, and means to maintain the center of oscillation of the needle at 100 all times in the center line of the stitches being formed.

105 2. In a buttonhole sewing machine, the combination with work-holding means movable only in the direction of the length of the 110

- buttonhole of stitch-forming mechanism arranged to form edge stitches on the two edges of the buttonhole in succession and barring stitches at the end of the buttonhole, 5 said stitch-forming mechanism including an oscillatory needle carrier, and means to maintain the center of oscillation of the needle carrier at all times in the center line of the stitches being formed.
- 10 3. In a buttonhole sewing machine, the combination with work-holding means movable only in the direction of the length of the buttonhole stitch-forming mechanism arranged to form the edge stitches along the 15 side of the buttonhole and barring stitches at the end of the buttonhole, said stitch-forming mechanism including an oscillatory needle bar carrier, and means to maintain the center of oscillation of the needle bar carrier 20 in the center line of the edge stitches as they are formed and in the center line of the buttonhole as the barring stitches are formed.
4. In a buttonhole sewing machine, the combination with stitch-forming mechanism 25 constructed to form edge stitches along the side of the buttonhole and barring stitches at the ends of the buttonhole, said stitch-forming mechanism including an oscillatory needle bar carrier, of means to shift the 30 needle bar carrier laterally and to maintain it in such position as the stitches are formed that the center of oscillation of said carrier is in the center of each stitch as it is formed.
5. In a buttonhole sewing machine, the 35 combination with stitch-forming mechanism constructed to form edge stitches at the sides of the buttonhole and barring stitches at the end of the buttonhole slit, said stitch-forming mechanism including an oscillatory 40 needle bar carrier, and means to shift the needle bar carrier bodily thereby to maintain the center of oscillation on that side of the buttonhole slit on which the edge stitches are being formed and while they are being 45 formed, and in the center line of the buttonhole while the barring stitches are being formed.
6. In a buttonhole sewing machine, the 50 combination with work-holding means, of stitch-forming mechanism constructed to form edge stitches at the sides of the buttonhole and barring stitches at the ends of the buttonhole, said stitch-forming mechanism including an oscillatory needle bar carrier, 55 means to produce a relative feeding movement between the stitch-feeding mechanism and work-holding means, said needle bar carrier being mounted for bodily movement transversely to the direction of feeding 60 movement, a toggle lever device by which the needle bar carrier is given its transverse movement, and means controlling the toggle lever device to maintain the center of oscillation of the carrier in the center line of 65 the stitches being formed.

7. In a buttonhole sewing machine, the combination with work-holding means, of stitch-forming mechanism arranged to form the edge stitches on the buttonhole and also barring stitches, said stitch-forming mechanism including an oscillatory needle bar carrier, means to produce a relative feeding movement between the stitch-forming mechanism and work-holding means, said needle bar carrier being movable in a direction 70 transversely to the feeding movement, a toggle lever device for shifting the needle bar carrier laterally, and means controlling the toggle lever device to maintain automatically the center of oscillation of the 75 needle bar carrier in the center line of the stitches being formed.

8. In a buttonhole sewing machine, the combination with work-holding means, of stitch-forming mechanism arranged to form 80 the edge stitches on the buttonhole and also barring stitches, said stitch-forming mechanism including an oscillatory needle bar carrier, means to produce a relative feeding movement between the stitch-forming mechanism and work-holding means, said needle bar carrier being movable in a direction 85 transversely to the feeding movement, a toggle lever device for shifting the needle bar carrier laterally, and means controlling the toggle lever device to maintain the center 90 of oscillation of the needle bar carrier in the center line of the edge stitches as they are formed and in the center line of the buttonhole as the barring stitches are formed.

9. In a buttonhole sewing machine, the combination with work-holding means, of a single needle stitch-forming mechanism and means to actuate the latter to form edge 95 stitches along the edge of the buttonhole and barring stitches of different lengths, all of which are centrally located with reference to the buttonhole.

10. In a buttonhole sewing machine, the combination with work-holding means, of stitch-forming mechanism by which the edge 100 stitches are formed on first one side of the buttonhole and then on the other and means to actuate the latter to form edge stitches along the edge of the buttonhole, and barring 105 stitches of different lengths with the center of each barring stitch in the center line of the buttonhole.

11. In a buttonhole sewing machine, the combination with work-holding means, of stitch-forming mechanism by which the edge 110 stitches are formed on first one side of the buttonhole and then on the other and means to actuate the latter to form edge stitches along the edge of the buttonhole, and barring 115 stitches of two different lengths with the center of each barring stitch in the center line of the buttonhole.

12. In a buttonhole sewing machine, the combination with work-holding means, of 120

stitch-forming mechanism for forming edge stitches along the sides of the buttonhole and for forming at each end of the buttonhole some barring stitches of the same length as 5 the edge stitches and some barring stitches of a greater length and for placing each barring stitch so that its center is in the center line of the buttonhole.

13. In a buttonhole sewing machine, the 10 combination with work-holding means, of stitch-forming mechanism including an oscillatory needle bar carrier, means to give said carrier a predetermined amplitude of oscillation during the formation of the edge 15 stitches and part of the barring stitches, and a greater amplitude of movement during the formation of all the remaining barring stitches.

14. In a buttonhole sewing machine, the 20 combination with work-holding means, of stitch-forming mechanism including an oscillatory needle bar carrier, means to give said carrier a predetermined amplitude of oscillation during the formation of the edge stitches 25 and part of the barring stitches, and a greater amplitude of movement during the formation of the remaining barring stitches, and means to maintain the center of oscillation in the center of the buttonhole while the 30 barring stitches are being formed.

15. In a buttonhole sewing machine, the combination with work-holding means, of 35 stitch-forming mechanism including an oscillatory needle bar carrier, means to give said carrier a predetermined amplitude of oscillation during the formation of the edge 40 stitches and part of the barring stitches, and a greater amplitude of movement during the formation of the remaining barring stitches, and means to maintain the center 45 of oscillation of the needle bar carrier in the center line of the stitches being formed.

16. In a buttonhole sewing machine, the 50 combination with work-holding means, of stitch-forming mechanism including an oscillatory needle bar carrier, means to give said carrier a predetermined amplitude of oscillation during the formation of the edge 55 stitches and part of the barring stitches, and a greater amplitude of movement during the formation of the remaining barring stitches, and means to maintain the center of oscillation of the needle bar carrier in the center line of the edge stitches as they are formed and in the center line of the buttonhole as 60 the barring stitches are formed.

17. In a buttonhole sewing machine, the 65 combination with stitch-forming mechanism including an oscillatory needle bar carrier, of means to oscillate said carrier, automatic means to increase the amplitude of oscillation at each end of the buttonhole thereby to form long barring stitches, and means to shift the needle bar carrier bodily and there- 70 by maintain the center of oscillation of said

needle bar carrier in the center line of the stitches being formed regardless of the length of said stitches.

18. In a buttonhole sewing machine, the combination with stitch-forming mechanism 75 and work-holding means, of a cam controlling the operation thereof whereby both edge stitches and barring stitches are formed, said cam having ratchet teeth and stop teeth, of an oscillatory member carrying a feeding 80 pawl which co-operates with the ratchet teeth, and a stop pawl co-operating with the stop teeth, said feeding pawl and stop pawl co-operating to feed the cam intermittently and to bring it to rest at the end of each 85 feeding movement.

19. In a sewing machine, the combination with stitch-forming mechanism and work-holding means, of a cam by which the operation of the machine is controlled, of a pawl-and-ratchet device for feeding the cam intermittently, and means co-operating with said pawl-and-ratchet device to bring the cam 90 positively to rest at the end of each forward movement.

20. In a sewing machine, the combination with stitch-forming mechanism and work-holding means movable relative to each other, of a cam by which such relative movement and the operation of the machine is 95 controlled, a pawl-and-ratchet device for feeding the cam intermittently and a stop pawl co-operating with said pawl-and-ratchet device to bring the cam positively to rest at the end of each forward step.

21. In a sewing machine, the combination with stitch-forming mechanism and work-holding means having a relative movement, of a cam by which such relative movement and the operation of the machine is controlled, a pawl-and-ratchet device for feeding the cam intermittently, stopping means co-operating with said pawl-and-ratchet device to bring the cam positively to rest at the end of each forward movement, and 105 means to render the stopping means inoperative during the backward movement of the feeding pawl.

22. In a sewing machine, the combination with stitch-forming mechanism, of a cam 110 controlling the operation thereof, whereby both edge stitches and barring stitches are formed, a friction feed device for intermittently feeding the cam during the formation of the edge stitches, a pawl-and-ratchet feed 115 device for feeding said cam at a higher rate of speed during the formation of the barring stitches, and means co-operating with the pawl-and-ratchet device to bring said cam positively to rest at the end of each forward 120 step and while the barring stitches are being formed.

23. In a buttonhole sewing machine, the combination with stitch-forming mechanism, of a cam controlling the latter so that both 125

edge stitches and barring stitches are formed, a feeding device for giving the cam an intermittent feeding movement during the formation of the edge stitches, a separate pawl-and-ratchet feeding device for giving the cam a faster intermittent movement during the formation of the barring stitches, and means co-operating with the pawl-and-ratchet feeding device to bring the cam 5 variably to a predetermined position when the barring stitches are completed.

24. In a buttonhole sewing machine, the combination with stitch-forming mechanism, of a cam controlling the latter so that 15 both edge stitches and barring stitches are formed, a pawl-and-ratchet feeding device for feeding the cam during the formation of the barring stitches, and means co-operating with said pawl-and-ratchet feeding 20 device to bring the cam positively to rest at the end of each forward movement.

25. In a buttonhole sewing machine, the combination with stitch-forming mechanism, of a cam controlling the latter so that 25 both edge stitches and barring stitches are formed, a feeding device for giving the cam a feeding movement during the formation of the edge stitches, said cam having ratchet teeth and stop teeth, an oscillatory member carrying a feed pawl which co-operates with the ratchet teeth to feed the cam during the formation of the barring stitches, and a stop pawl co-operating with the stop teeth, said feeding pawl and stop pawl operating to feed the cam intermittently and to bring it to rest at the end of each feeding movement.

26. In a buttonhole sewing machine, the combination with stitch-forming mechanism by which both the edge stitches and barring stitches are formed, of a cam controlling said mechanism, a feeding device for feeding the cam during the formation of the edge stitches, a pawl-and-ratchet device for feeding the cam intermittently during the formation of the barring stitches, and a stop pawl co-operating with said pawl-and-ratchet device to bring the cam positively to rest at the end of each forward step.

27. In a buttonhole sewing machine, the combination with stitch-forming mechanism by which both the edge stitches and barring stitches are formed, of a cam controlling said mechanism, a feeding device for feeding the cam during the formation of the edge stitches, a pawl-and-ratchet device comprising an oscillatory feed pawl for feeding the cam intermittently during the formation of the barring stitches, a stop pawl co-operating with said pawl-and-ratchet device to bring the cam positively to rest at the end of each forward step, and

means to render the stop pawl inoperative during the backward movement of the feed 65 pawl.

28. In a buttonhole sewing machine, the combination with stitch-forming mechanism, of a cam device controlling the latter so that both edge stitches and barring 70 stitches are formed, said cam having ratchet teeth corresponding in number to the number of barring stitches, an oscillatory feed pawl co-operating with said teeth to feed the cam forward during the formation 75 of barring stitches, said feed pawl having an amplitude of movement equal to the distance between the ratchet teeth, and means to prevent the cam from overrunning at the end of each forward movement.

29. In a buttonhole sewing machine, the combination with stitch-forming mechanism, of a cam device controlling the latter so that both edge stitches and barring 85 stitches are formed, said cam having ratchet teeth corresponding in number to the number of barring stitches, an oscillatory feed pawl co-operating with said teeth to feed the cam forward during the formation 90 of barring stitches, said feed pawl having an amplitude of movement equal to the distance between the ratchet teeth, and means to bring the cam positively to rest at the end of each forward movement

30. In a buttonhole sewing machine, the combination with stitch-forming mechanism, of a cam controlling the latter so that both edge stitches and barring stitches are formed, said cam having a plurality of ratchet teeth equal in number to the number of barring stitches to be formed, means to feed the cam forward for each barring 95 stitch a space equal to the distance between adjacent ratchet teeth, and to bring the cam to rest at the end of each forward movement.

31. In a buttonhole sewing machine, the combination with stitch-forming mechanism, of a cam controlling the latter so that both edge stitches and barring stitches are formed, said cam having a plurality of ratchet teeth equal in number to the number of barring stitches to be formed, an oscillatory pawl carrier having an amplitude 110 of movement equal to the distance between adjacent ratchet teeth, a pawl carried thereby co-operating with said ratchet teeth to feed the cam forward intermittently during the formation of the barring stitches, and means carried by the pawl carrier to bring the cam to rest positively at the end 115 of each forward movement.

In testimony whereof, I have signed my name to this specification.

FRANKLIN A. REECE.
